UNITED STATES PATENT OFFICE.

WILLIAM F. ROEHLIN, OF ROCHESTER, NEW YORK.

METHOD AND APPARATUS FOR PRINTING MATERIALS.

Application filed September 15, 1924. Serial No. 737,712.

This invention relates to methods and apparatus for printing materials and, more particularly, to the variety adapted, for example, for printing patterns and designs on fabric, leather, and the like, one object of the invention being to provide an improved method and apparatus of this nature of a simple and practical character in use and adapted to produce a more perfect and permanent product. Another object is the provision of such a method and apparatus particularly adapted for printing with a medium, such, for example, as an anilin color, requiring the application of heat in printing to develop and fix the color in the material. Another object is the provision of a method and apparatus of the above nature especially suitable for use in conjunction with the production of goffering or embossed effects in the material. Still a further object is the provision of an apparatus and method combining the above advantages with a continuous character of operation capable of accomplishing the work in a rapid and economical manner.

To these and other ends the invention resides in certain improvements and combinations of parts, all as will be hereinafter more fully described, the novel features being pointed out in the claims at the end of the specification.

In the drawings:

Figure 1 is a central sectional elevation of an apparatus or press embodying the present invention;

Figure 2 is a side view of roller means employed in the apparatus and

Figure 3 is a detailed view of a portion of the material produced.

Similar reference numerals throughout the several views indicate the same parts.

The present invention is in the nature of an improvement on that disclosed in my co-pending application for Letters Patent, Serial No. 613,147, filed January 17, 1923, for apparatus for and method of printing materials. While my said prior invention has various advantages, the present improvements provide for the use of a higher temperature without undue heating of the printing roller and at the same time provide for the application of a relatively high tempera-

ture directly to the face side of the material and to the surface portions to which the printing medium has been applied so that the latter may be more effectively heated for developing and completing the impression as well as for the production of embossing effects in conjunction with the same.

Referring more particularly to the drawings, for a description of one form of apparatus for carrying out my said method, there is shown at 5 one of a pair of spaced side standards rising from a base 6 and connected by tie rods 7 to form the main frame 65 for the apparatus. These side standards have fixed thereon at the forward side of the machine bearing brackets 8 in which are rotatably supported journals 9 at the ends of a platen means or roller 10 more particularly described hereafter. Above and below the roller 10 side frames 5 are formed with ways 11 on which are slidably supported and guided upper and lower pairs of shoes 12 and 13, respectively. Each of the pair of oppositely spaced lower shoes 13 carries a bearing bracket 14 in which is rotatably supported a journal 15 at the corresponding end of a printing roller 16. Each shoe 13 is supported from below by the engagement of a boss 17 thereon with the upper end of a spindle 18 in threaded engagement with a stationary supporting arm 19 projecting forwardly from the frame. It is apparent that by rotating each spindle 18, as by means of a hand wheel 20 thereon, the corresponding shoe 13 and an end of the printing roller may be raised or lowered as required to maintain the desired parallelism and pressure between the printing roller and the platen roller 10.

Printing roller 16 may have its impression surface formed and supplied with a suitable printing medium in various ways. In the present instance, and for certain kinds of work, it is preferred to form the matter to be printed in intaglio on the roller surface and to supply such intaglio portions with the printing medium. More specifically, roller 16 has the elements of the pattern or the matter to be printed engraved in intaglio thereon as represented in the drawings in an illustrative way by flags 21 and triangles 22.

Devices are provided for applying a suit-

able printing medium to the printing roller comprising preferably a container 23 supported in any suitable manner as by being bolted to and supported by an angle bar 24 5 carried at its ends on the side standards of the frame. The printing roller dips at its bottom into the printing medium in container 23, it being understood that the necessary vertical adjustment of the printing roller is 10 comparatively small so that such adjustment does not interfere with the operation of this supply means. The latter however could of course be carried by the shoes 13, if desired, to move with the roller. At 25 is a doctor 15 for removing the medium from the relief portions of the roller and leaving it in the intaglio portions representing the design. This doctor is carried as shown by a bracket 26 on the container.

20 Means are desired, under some conditions of operation, for cooling the printing roller, for which purpose the latter is preferably of the hollow metal construction indicated in the drawings and its journals 15 are also of 25 hollow or tubular construction in communication with the roller interior. Piping 27 is connected in any suitable manner with the ends of these journals, as well understood in the art, and with a source of supply of a 30 cooling fluid such as water or brine for maintaining a continuous circulation of the latter through the roller to keep it at a relatively low temperature.

35 The heating and embossing roller is shown at 28 above the platen roller 10 and its journals 29 are rotatably supported in bearing brackets 30 carried by the upper pair of adjustable shoes 12. Each of the latter is supported by the rotatable engagement of a boss 40 31 thereon with the lower end of a spindle 32 threadedly engaged with a stationary supporting arm 33 projecting forwardly from the top of each of the frame standards. By rotating the spindles, as by means of 45 hand wheels 34 thereon, the ends of roller 28 may be adjusted to secure the desired parallelism with and pressure against the top of platen roller 10.

50 Heating roller 28 is preferably engraved in intaglio with the matter to be printed to correspond with the printing roller 16. The printing and heating rollers are preferably of the same circumference, or a multiple circumference one of the other and platen roller 55 10 is preferably of the same or a multiple circumference relative to rollers 16 and 28, having in the present instance a circumference twice that of either of these rollers. Such relative proportions are for the purpose 60 of maintaining registry between the intaglio portions of roller 28 and the portions of the material to which printing medium has been applied by the roller 16, as well as between the printing and heating rollers and 65 the platen roller as useful in some forms of

construction. To this end the journals of the several rollers are connected by intermeshing gears 35, 36 and 37 to maintain such registry, the material web indicated at 38 being passed rearwardly between the printing roller and the platen roller 10 with its face or pile side against the printing roller and thence upwardly around the platen roller between it and heating roller 28 with its face side against the latter and thence rearwardly for suitable disposition of the completed web. It is apparent from this arrangement that the same surface of the material to which the printing medium is applied by the printing rollers is brought directly against the surface of the heating roller so that the heat of the latter is applied to the portions of the material carrying the printing medium for more effectively heating the latter, as well as embossing the 85 same in conjunction with the printing where such a result is desired. Heat is applied to roller 28 by the use of hollow journals as described in connection with the printing roller, such journals being connected as by 90 means of piping 39 with a suitable source of steam, hot water or other heating fluid.

Platen roller 10 may be constructed of steel with a smooth surface but it is preferred for best results to employ a form of 95 construction comprising a surface of relatively soft material tending to become formed by the rollers 16 and 28 in a manner complementary to the engraving of the latter through the pressure applied thereby, or 100 in other words with a male formation corresponding to the female character of rollers 16 and 18. Thus roller 10 may be constructed of papier mâché or, as shown in the drawings, it may be constructed of steel and surfaced with yielding material such, for example, as one or more plies or wrappings of fabric. One advantage of this latter construction is that plies of thin wrapping material or cloth may be added to or removed 110 from the roller surface in operation to increase or diminish its circumference for the purpose of correcting and maintaining precise registry between the impressions of the printing roller 16 and the corresponding engraving of the heating and embossing roller 28. As will be understood by those skilled 115 in the art, the web of the material to be printed may vary from time to time in its texture and characteristics with the result of a tendency to disturb such registry and this difficulty has been satisfactorily overcome in this manner which at the same time affords the desired plasticity.

Figure 3 illustrates in a general way a 125 portion of the material 40 to be treated while at 41 is a portion of the area to which the printing medium has been applied. As the material passes around roller 28 heat is applied to it by the latter directly adjacent and 130

over the portions bearing the printing medium so that the latter may be effectively heated to any desired temperature. By applying sufficient pressure by roller 28, furthermore, a goffering or embossing result, particularly with pile fabric, may be obtained in combination with the printing to afford highly ornamental results, as fully described in my said prior application.

10 The present method and apparatus have furthermore been found advantageous for use with a printing medium requiring heat treatment to secure thorough impregnation and also to produce desired changes in the medium as, for example, the development of colors in anilin substances. It is apparent from the above description that such a printing medium may be applied to the material in substantially cold condition and 15 subsequently heated to a relatively high temperature by the application of heat directly to the portions of the material to which the medium has been applied for the purpose of producing such developing 20 changes in the medium as may be desired to insure a complete and permanent impression.

The operation of the apparatus for carrying out the method as well as the steps of 25 the latter have been fully explained in connection with the above description and it is apparent that the invention provides a method and apparatus of a comparatively simple nature adapted to operate in a continuous, rapid and efficient manner to accomplish the desired results.

I claim as my invention:

1. In apparatus of the character described, 30 the combination of a pair of engraved rollers provided with means for maintaining the relative registry therebetween, means for pressing the same side of a material to be printed against said rollers in succession, devices for applying a printing medium 35 to the first of said rollers and means for heating the second roller, to first print said material and then heat the printed surface to complete the impression.

2. In apparatus of the character described, 40 the combination of a roller provided with means for applying a printing medium thereto to represent matter to be printed, a second roller having the matter to be printed formed in intaglio in its surface and having means for heating the same, and means for pressing a material to be printed against said rollers in succession with said printed matter thereon in registry with the intaglio 45 portions of said second roller.

3. In apparatus of the character described, 50 the combination of a roller provided with means for applying a printing medium thereto to represent matter to be printed, a second roller having the matter to be printed formed in intaglio in its surface and having

means for heating the same, and means for pressing the same side of a material to be printed against said rollers in succession with said printed matter thereon in registry with the intaglio portions of said second 55 roller.

4. In apparatus of the character described, the combination of a roller having matter to be printed formed in intaglio on its surface and provided with means for applying a 60 printing medium to said intaglio portions, a second roller having a similarly formed surface and provided with means for heating the same, and means for pressing the same side of a material to be printed against said rollers in succession with said printed matter thereon in registry with said intaglio 65 portions of said second roller.

5. In apparatus of the character described, the combination of a roller having matter 70 to be printed engraved thereon, devices for applying a printing medium to said roller, a second roller similarly engraved and provided with heating means, and roller means for pressing the same side of a material to 75 be printed against said rollers in succession with the matter printed thereon by said first roller in registry with the engraving of the 80 same on said second roller.

6. In apparatus of the character described, the combination of a roller provided with 85 means for applying a printing medium thereto to represent matter to be printed, an embossing roller having the matter to be printed engraved thereon and provided 90 with heating means, roller platen means for operating with said printing and embossing rollers comprising a surface of relatively 95 soft material tending to conform to the engraved surface of said embossing roller, and operating means for rotating said rollers and roller platen means to continuously and progressively 100 press the material to be printed against said rollers in succession with the matter printed on the material in registry 105 with the engraving of the same on said embossing roller.

7. In apparatus of the character described, the combination of a roller having matter 110 to be printed engraved in intaglio thereon, devices for applying a printing medium to said intaglio portions, an embossing roller similarly engraved and provided with heating means, roller platen means cooperating 115 with said rollers having a surface of relatively soft material tending to be formed in complementary character by the engraving of said rollers, and operating means for rotating said rollers and roller platen means to 120 continuously and progressively effect a registered printing and embossing of the same side of the material.

8. The method of printing a material consisting in continuously and successively impressing the same first with a rotary print- 125

ing roller supplied with a printing medium and subsequently with a rotary heating roller engraved with the matter to be printed and maintaining registry between the matter printed on said material and the engraving on said roller.

9. The method of printing a material consisting in continuously and successively im-

pressing the same first with a roller formed with inked intaglio portions representing the matter to be printed and subsequently with a heating and embossing roller similarly formed and maintaining registry between the matter printed on the material and the intaglio portions of said heating roller.

WILLIAM F. RÖEHLÉN.
